UNITED STATES PATENT OFFICE.

WILLIAM WESTLAKE, OF BROOKLYN, N. Y., ASSIGNOR TO THE UNITED STATES COMBUSTION COMPANY, OF NEW YORK.

FURNACE FOR BOILERS.

SPECIFICATION forming part of Letters Patent No. 328,991, dated October 27, 1885.

Application filed June 21, 1884. Serial No. 135,622. (No model.)

To all whom it may concern

Be it known that I, WILLIAM WESTLAKE, a citizen of the United States, residing at Brooklyn, in the county of Kings and State of New York, have invented certain new and useful 5 Improvements in Furnaces for Boilers, &c., of which the following is a specification.

My invention relates to that class of apparatus in which currents of heated air are introduced among the products of combustion for the purpose of insuring a consumption of the carbonaceous portions and the prevention of smoke; and my invention consists in means, fully set forth hereinafter, whereby to introduce the air in a highly-heated state thoroughly among the gases without interfering with the free draft, without chilling the gases, and without injury to the apparatus.

In the drawings, Figure 1 is a sectional elevation of a vertical tubular boiler illustrating my improvement. Fig. 2 is a sectional elevation of a horizontal boiler, and showing my improvement in connection therewith. Fig. 3 is an enlarged sectional view of the air-distributing device. Fig. 4 is a sectional view of said device at right angles to the section, Fig. 3. Fig. 5 is a plan of the ring of the air-distributing device. Fig. 6 is a plan of the branch pipe of the air-distributing device.

In some classes of smoke-preventing apparatus it is common to distribute heated air among the products of combustion by means of perforated pipes, bridge-walls, diaphragms, &c., extending across the fire-place. These 30 structures are apt to interfere with the draft, and result sometimes in chilling the gases, while the introduction of the air along a single plane does not result in thoroughly intermingling it with the gases. In other apparatus jets of air are forced through nozzles at the sides or front of the fire-place into the gases arising from the fuel. This does not effect a complete combination of the air and gases near the center of the fire-place unless a strong lateral blast is used, which is objectionable, as it interferes with the direct draft, and sometimes by chilling the gases causes the escape of part of the carbonaceous matter unconsumed in the form of smoke, it being essential to the prevention 45 of smoke that the gases be consumed before

they enter the flues. To effect a thorough consumption of the gases I introduce the highly-heated air in streams or jets flowing outward from about the center of the combustion-chamber, or radially both outward and inward, so 55 as to thoroughly intermingle with the products of combustion at the points where they are at the greatest heat, and cause the most intense combustion at the inside shell of the boiler; and I use an air-distributer so constructed and arranged as to retain the heat and supply heated-air currents without materially changing the course of the gases or interfering with their free flow.

My invention is applicable to furnaces of different kinds and constructions, and wherever the introduction of currents of highly-heated air among the products of combustion in the fire-place will facilitate the combustion of the gases; but for purposes of illustration I have 60 shown in Fig. 1 the application of the invention in connection with a vertical tubular boiler, and in Fig. 2 in connection with a horizontal boiler. The air is conducted to and distributed by a head or distributer, A, which 65 is suspended or secured at about the center of the combustion-chamber X, the latter in Fig. 1 being directly over the grate B, and in Fig. 2 being beyond the bridge-wall C. The distributer A is a hollow head extending nearly 70 to the walls of the combustion-chamber, and so constructed, of any suitable shape, that the air may flow therefrom through orifices or perforations x, suitably arranged, and the tube or conduit D, through which the air passes to 75 the distributer, extends through one or more chambers, Y, either inclosed within the casing of the boiler E or within the uptake F, so that the air passing through such tube is preliminarily heated by the gases flowing through 80 said chambers. In order that the air before escaping may be heated to as great a degree as possible, the distributer A is placed at the point where the combustion is most intense, in position for the gases to flow round the 85 same on all sides, and to protect the distributer against the destructive effects of the highly-heated gases which strike the same on their way from the fire-place, and to retain the heat, I provide the same with a shield or guard, G, 90

of fire-clay or other refractory material, so placed that the said gases will impinge upon the same. In the drawings the distributer is shown as consisting of a cast-metal ring, of such 5 shape as, with the guard G, to inclose an annular chamber, w, to which the air can flow from a central stem, a, through branches b b', the stem a being connected to the pipe D, through which the air is supplied. The guard G is in 10 two or more sections, confined against the open side of the ring by means of bolts c, the heads of which lie within sockets or openings formed in the guards and filled with fire-clay v, or other refractory material, which protects 15 the heads from the direct action of the heated gases, thereby preventing them from being burned away, and the air-channels are formed by grooving the face of the guard at the points where it is in contact with the edges of the ring. 20 It will be noticed that the air-channels x are inclined away from the fire-grate or toward the flue, so that the currents of heated air will not be thrown directly against the sides of the combustion-chamber, or counter to the direction in which the products of combustion 25 flow from the fire-place, and there is no tendency to act with a blow-pipe effect against the shell of the boiler, nor any retarding of the currents that would interfere with the draft. At the same time the gases are directed 30 outward, so that the most intense combustion is at the side of the boiler-shell. The air is forced into the distributer by means of a blower, I, which is of such a character and 35 operated at such a speed as to insure a free but easy flow of the air, the object being to supply an abundant quantity of air to the gases without producing any blast liable to carry away the products of combustion un- 40 consumed. It is important to provide for the natural flow of the air into the distributer should the movement of the blower be arrested, for which reason I employ a fan, a "Black- 45 man" fan being shown, through which the air can pass onward to the supply-tube, even when the fan or blower is at rest. It will be seen that the currents of air flowing through the inner channels, x, might act with a de- 50 structive effect against the branches b b', to- 55 ward which said currents are projected. I therefore, to prevent injury from such a cause, insert a plate of refractory material, J, be- 60 tween the branches, so as to prevent such action, sufficient space being left between the plate and the ring for the gases to flow later- 65 ally outward. In some cases the inner chan- 6c nels may be dispensed with, the guard then consisting of a solid disk. As the distributer A is arranged at that point in the combustion- 6c chamber where the heat is most intense, the air before passing through the channels is brought to a very highly-heated condition, approximating the temperature of the products of combustion, so that there is no chill- 65 ing of the latter from the introduction of the air, but, on the contrary, a thorough combus- 6c tion of the carbonaceous matter is effected.

By the arrangement of channels x-x' the air is caused to flow both inwardly and outwardly from the distributer, and it is thoroughly inter- 70 mingled with the gases, not only at the sides of the combustion-chamber, but also at the center, so that no portion of the products of combustion escapes without admixture with the air. The preliminary heating of the air 75 prior to its passage into the distributer is important, as thereby the chilling of the distributer is prevented, and when the conducting or supply pipe D extends through the boiler, as shown in Fig. 1, and in contact with 80 the water, this preliminary heating of the air further tends to heat the boiler-tube and secure an increased evaporation of the water. The guard G is of such size as to retain the heat, so that the distributer does not become 85 chilled from the opening of the furnace-door in feeding, or from the placing of fresh coal upon the fire. This is most important, as thereby the volume of smoke emitted when fresh fuel is added is thoroughly consumed, 90 while in ordinary apparatus the air-distributors are generally chilled at such times when it is most essential for them to be in a highly-heated condition.

In Fig. 1 an air-heater, K, is shown as ar- 95 ranged within the uptake, and consists of an annular shell, f, communicating with the inlet- 100 pipe, and a hollow casing, f', communicating with the pipe D, and small pipes or tubes g, connecting the casing and shell. By this construction the heated gases flowing through the uptake warm the air, while those within the chamber y impart a considerably higher tem- 105 perature, so that it reaches the distributer A in a comparatively hot state. In some in- 110 stances it is desirable, in order to secure a more intense heat, to supply the air-current with car- 115 bon in a finely-divided form—as, for instance, in the shape of a liquid or fine dust. To effect this I employ a reservoir, L, from which a pipe, k, extends into the conducting-pipe at any suitable point, so that the inflowing cur- 120 rent of air will carry with it the fluid or par- 125 ticles passing from the pipe k, a valve, l, reg- 130 ularizing the flow of the carbonaceous mate- rial.

The construction of distributer above de- 130 scribed is especially adapted for use where such carbonaceous material is supplied to the air-current, as it permits ready access to the 140 chamber w to cleanse the same by the removal of the refractory guard G.

When desired, the perforations may be made in the guard G to permit currents of air to flow through the same, as shown in Fig. 2.

When it is desired to introduce a combined current of steam and air, a steam-pipe, N, may be passed through the air-supply pipe D at any point, so as to direct the steam into the air as it flows through said pipe.

I am aware that perforated air-pipes have been extended into the combustion-chambers of furnaces; but these are of such limited dimensions that but a small portion of the gases

can be combined with the fresh-air currents, while by using an expanded head suspended centrally within the chamber and exposed at the ends and sides to the action of the flames, 5 the air is made much hotter and more thoroughly mingled with the gases than is possible with an ordinary tube.

I am aware that a perforated air-ring supplied by a laterally-propelling tube has been 10 arranged within the combustion-chamber of a furnace; but the lateral tube interferes with the free flow of air, and is apt to be burned away, having no protection. As such air-distributors occupy a large space, they interfere 15 with the draft, and are objectionable for that reason; but by supplying them with air by means of a blowing apparatus an artificial draft is created, which compensates for the obstruction.

20 Without limiting myself to the precise construction and arrangement of parts shown, I claim—

1. The combination, with a furnace, of an air-blowing apparatus, an air-distributing head suspended centrally within the combustion-chamber adjacent to but beyond the grate, arranged to leave a surrounding unobstructed 25 passage, and provided with channels communicating with the blastapparatus, and arranged 30 to direct the air in currents among the products of combustion and away from the fire, substantially as set forth.

2. The combination of an air-blowing apparatus, an air-conducting tube, and an expanded 35 air-distributing head communicating with said tube and arranged centrally within the combustion-chamber of a furnace to leave a surrounding passage, and provided with channels 40 directing the air among the products of combustion away from the fire, the blowing apparatus being constructed and operating so as when at rest to permit a free flow of the air without any blast, substantially as set forth.

3. The combination, with a furnace, of a 45 blowing apparatus, an air-distributing head

provided with perforations through which the air can flow among the products of combustion, the said distributor being arranged within the combustion-chamber and beyond the grate, with an uninterrupted surrounding passage, 50 with its end toward the fire-bed, and so as to be surrounded on all sides by the gases flowing to the chimney, and provided with channels arranged to direct the jets on all sides against a stationary portion of the furnace between the tubes and fire-bed, substantially as set forth.

4. The combination, with a furnace, of a blowing apparatus and an air-distributer communicating therewith, and arranged centrally 60 within the combustion-chamber to be exposed on all sides to the hot gases, and provided with channels arranged to direct the air in currents both outward and inward in said chamber and against a stationary portion of the furnace, 65 substantially as set forth.

5. An air-distributer for furnaces, consisting of a hollow ring open at the bottom and provided with channels upon its inner and outer sides, and with a refractory guard upon the 70 open side of said ring, substantially as set forth.

6. The combination, in an air-distributer, of a perforated hollow ring, a guard of refractory material, and an air-pipe leading to and 75 communicating with the ring at the side opposite the guard, to leave an uninterrupted surrounding passage, substantially as set forth.

7. The combination, with an air-distributer, of a guard of refractory material, connecting bolts passing through sockets in said guard, and refractory fillings in said sockets over the heads of the bolts, for the purpose specified.

In testimony whereof I have signed my name to this specification in the presence of two sub- 85 scribing witnesses.

WILLIAM WESTLAKE.
